UNITED STATES PATENT OFFICE.

FRED O. PERMIN, OF NEW YORK, N. Y.

AMUSEMENT DEVICE.

1,413,349.

Specification of Letters Patent. Patented Apr. 18, 1922.

Application filed October 4, 1920. Serial No. 414,646.

To all whom it may concern:

Be it known that I, FRED O. PERMIN, a citizen of the United States, residing at 524 West One Hundred Twenty-third Street, in the city, county, and State of New York, have invented certain new and useful Improvements in Amusement Devices, of which the following is a specification.

This invention relates to a machine which is so constructed and operated that it gives the appearance of birds flying in a horizontal line and has for its object to provide means for causing said moving objects to travel in a predetermined path of movement, and further to provide operating parts and other forms of construction to cause these moving objects to stop when reaching their ends of path of movement and rebound and again stop at points in their return movement predetermined by the inertia of their rebound, or at points in their forward path of movement before they reach the limit of their path of movement:—and again to provide means to adjust said movable parts to their normal positions.

This invention consists of other novel features of construction and arrangements of parts to be hereinafter fully set forth and particularly pointed out in appended claims.

In order to clearly describe this invention reference must be had to the accompanying drawings which taken in connection with this specification form part of this application.

Like numerals of reference indicate like parts in the several figures of the drawings, of which:—

Fig. 1 is a front elevation of the invention;

Fig. 2 is a side elevation of same;

Figs. 3—4—5 are details of the operating and releasing parts, enlarged;

Fig. 6 is an enlarged detail of the frame construction;

Fig. 7 is a longitudinal section through the primary operating parts;

Fig. 8 is a detail of the starting means;

Fig. 9 is a detail of the stopping means, and

Figs. 10—11—12 details of the carriage.

In the practice of this invention I employ side-frames 2 which are spaced apart by spreaders 3—4: said spreaders having attached thereto trunnions 5 to support beams 6—6^a which are grooved to receive said trunnions and are fastened thereto by bolts 7

which also pass through caps 8; said caps being counterparts of beams 6—6^a.

Attached to beams 6—6^a are brackets 9 to which are pivoted pulleys 10; said pulleys having pendant hammers 11 integrally fastened thereto; said hammers registering with heads 12 of pins 13 when operated by cords 14 which pass downwardly to engage pulleys 15 and thence upwardly and over pulleys 16 thence to hollow knob 17 into which they are fastened by suitable means such as a knot as shown at 18:—said pulleys 16 are pivoted within housings 19 which are fastened to counter 20: said counter being supported by uprights 21—21^a which rest on floor 22.

It will be noted that knobs 17 have integral therewith shanks 23 which are threaded to receive tubes 24 which slide into pipes 25; said pipes being attached to housing 19 as shown by a thread or other practical means.

A plurality of bearings 26 are attached to beams 6—6^a into which are placed tubes 27 which receive pins 13 and 28; said pins being separated by helical spring 55, while in Figure 8 it will be noted that there are two helical springs 29—30 spaced apart by means of cotter-pins 31:—said springs serving as shock-absorbers when tubes 27 are thrust forward or when they recoil in a counter direction.

Integral with bearings 26 are brackets 32 to which are fastened one end of wires 33 while their opposite ends pass through bearings 26 above tubes 27 and horizontally across to beams 6^a where they are fastened as shown in Figures 1 and 9 respectively.

Suspended from wires 33 are carriages 34 with a pendant 35 attached thereto: said pendant receiving rods 36 on which are hung objects such as birds 37 which are fixed thereto by collars 38 and set-screws 39 which are threaded into said collars to engage rods 36; said carriages being supported by sheaves 40 which are revolvably mounted intermediate carriages 34 and side-plates 41 by means of screws 42. The side-plates have fingers 43 horizontally integral therewith and a flexible member 44 attached thereto in a vertical line for purposes to be clearly described in another paragraph.

Fastened to beams 6—6^a are brackets 45—45^a to which are pivoted supports 46—46^a for square tubes 47 to which are fixed pins 48; immediately in front of which are

numbers 49 as shown at #8 in Figure 1. These pins act as stopping means when the carriages rebound, or stop them while in their forward path of movement, and the 5 numbers indicate the skill of the operator as shall be shown hereinafter.

Passing downwardly from supports 46—46^a are cords 50 which run over sheaves 51, thence horizontally to levers 52 which are 10 pivoted through shelf 53 for the purpose of releasing the movable objects and returning them to their normal positions by operating said levers forward to the broken line shown in Figure 2.

15 Wires 33 and tubes 47 are parallel but are arranged a trifle out of horizontal as shown in Figure 1, for the purpose of allowing the movable objects 37 to return to normal by their own gravity when released 20 from pins 48.

In order to operate this invention, tubes 24 are pulled outwardly by means of knobs 17: this in turn causes cords 14 to lift 25 hammers 11 upwardly and strike heads 12 of pins 13 compressing springs 29 which encircle that portion of tubes 27 which lie within chambers 54 of bearings 26 compressing springs 55 which lie intermediate pins 13 and 28 within said tubes 27 until pins 30 13 register with pins 28 which are reduced at 28^a forming shoulders 28^b which normally register with flanges 27^a of tubes 27. The arrangement of the pins, tubes and springs serve to "slide" (rather than "thrust") carriages 34 away from pins 28 on wires 33 while flexible members 44 bend to escape 35 pins 48 while carriages 34 move horizontally until they register with studs 56 which are 40 slidably mounted on wires 33, unless said carriages stop before reaching said studs. The forward inertia of said carriages causes 45 springs 57 to compress and recoil thus giving carriages 34 return inertia sufficient to move them backward until said return inertia is exhausted and each flexible member 50 stops at one of the pins 48, while the number in front of each pin indicates the skill of the operator. When the operator reads the 55 number with which he registers the person in charge of the machine moves levers 52 in such a position as to cause cords 50 to lift supports 46—46^a upwardly far enough to release flexible members 44 from contact with pins 48 and allow carriages 34 to return to normal.

There are six operating parts shown, while any number may be used, and each part acts independently of the others.

By observing Figure 6 it will be seen that 60 the frames are so constructed that they are flexible and can be easily adjusted to any floor or ground by means of unions 58 which are threaded at 59 into collars 60 and spreaders 3—4.

65 A salient feature of this invention is the

means of tightening wires 33 as may be observed in Figure 3; said tightening means consisting of threaded sleeves 61 which are fastened to one end of wires 33 and adjusted by check-nuts 62 which rest against brackets 70 32 of bearings 26. When said wires are tightened as above described it will become necessary to adjust tubes 47 parallel therewith, and for this purpose brackets 45—45^a have integral therewith lugs 63 through 75 which pass set-screws 64, the ends of which register with the under sides of supports 46—46^a to adjust said tubes parallel with wires 33.

In Figures 10—11—12 it will be seen that 80 there are bosses 65—65^a immediately under wires 33 integral with pendants 35 for the purpose of preventing wheels 40 of carriages 34 from "jumping" said wires in event that the operator strikes a violent 85 blow of hammers 11 and thereby prevents the normal movement of said carriages. It will be further noted that fingers 43 pass inwardly and under square tubes 47 so that when the carriages "rock" said fingers will 90 strike said tubes and quickly rebalance said carriage.

This invention may be constructed of any material and made any size deemed suitable for all the requirements of such a device, and while a preferred form of mechanism is illustrated and described, it is desired to include in this application all mechanical equivalents and substitutes that lie within the scope and purview of the appended claims.

Having thus fully described this invention so that others skilled in the art to which it appertains may be enabled to construct and use the same, what I claim and desire 105 to secure by Letters Patent is:—

1. The combination with side-frames of transverse beams attached to said side-frames; means fastened to said beams to support movable objects; said movable objects passing intermediate said beams; devices attached to the beams to start said movable objects; operating parts remote from said beams and side-frames; and means connecting said operating parts with 110 the starting devices; and means to stop and release said movable parts fastened intermediate said beams.

2. The combination with side-frames of transverse beams attached to said side-frames; means fastened to said beams to support movable objects; said movable objects passing horizontally intermediate said beams; devices attached to the beams to start said movable objects; manual operating parts remote from said beams and side-frames; means connecting said operating parts with the starting devices; and means 115 to stop and release said movable parts fastened intermediate said beams.

3. The combination with side-frames of transverse beams attached to said side-frames; means fastened to said beams to support movable objects; said movable objects passing intermediate said beams; devices attached to the beams to start said movable objects; operating parts remote from said beams and side-frames; means connecting said operating parts with the starting devices; means to stop said movable parts when their inertia is exhausted; and means to manually release said movable parts attached intermediate said beams. 4. The combination with side-frames of transverse beams attached to said side-frames; means attached to said beams to support movable pendant objects; means to start said objects attached to the beams; means to arrest said movable parts suspended intermediate the beams; manual operating parts remote from the beams and side-frames; means connecting said operating parts and starting devices with the beams; and means to return said movable parts to their starting positions pivoted to the beams. 5. The combination with side-frames of transverse beams attached to said side-frames; means fastened to said beams to support movable pendant objects; said objects passing intermediate the beams; starting devices for said movable parts attached to said beams; means to operate said starting devices remote from the beams and side-frames; means to connect said operating and starting devices with the beams; means within the path of movement of the movable objects to indicate their distance of travel; and means to return said objects to their starting positions attached to the beams. 6. The combination with side-frames of transverse beams attached to said frames; means fastened to said beams to support movable pendant objects; said objects passing intermediate the beams; driving-pins attached to said beams to normally register with one end of the movable objects; hammers pivoted to the beams to strike said driving-pins and start said movable objects; stopping and reverberating means attached to the beams remote from the driving-pins; operating means remote from the beams; devices to connect said hammers with the operating means; and levers to return said movable objects to their starting positions. 7. The combination with side-frames of transverse beams attached to said frames; wires fastened intermediate said beams to support movable pendant objects; said objects being adapted to slide on said wires; driving-pins slidably mounted to the beams and registering with one end of the movable objects; hammers pivoted to the beams to strike said driving-pins and start said movable objects; manual operating means remote from the beams to operate each movable object independently; cords connecting each operating device with each of the starting de-
- remote from the hammers; means to connect said hammers with operating means; means to stop said movable objects at points intermediate their complete distance of travel; means adjacent said intermediate stopping points to indicate the skill of the operator; levers pivoted to the beams to readjust said movable objects to their starting positions. 8. The combination with side-frames of transverse beams attached to said side-frames; wires fastened intermediate said beams to support movable pendant objects; said objects being adapted to slide on said wires; driving-pins slidably mounted to the beams and registering with one end of the movable objects; counterweighted hammers pivoted to the beams to strike said driving-pins and start said movable objects: thence automatically returning to normal; manual operating means remote from the hammers; cords connecting said hammers with the operating means; means to stop and reverberate said movable objects when they reach their extreme points of travel; flexible members attached to the movable objects to arrest their backward travel; means to register with said flexible members attached intermediate the beams; means to indicate the skill of the operator fixed adjacent said registering points; and levers pivoted to the beams to readjust all the movable objects to their starting positions simultaneously. 9. The combination with side-frames of transverse beams attached to said side-frames; wires fastened to said beams to support movable pendant objects; said objects being adapted to slide on said wires intermediate the beams; driving-pins slidably mounted to the beams and registering with one end of the movable objects; springs intermediate said driving-pins to readjust them to normal; hammers pivoted to the beams to strike said driving-pins and start said movable objects; means to return said hammers to normal; means to operate said hammers remote from the beams; cords connecting said operating means with the hammers; means attached to said beams to stop each movable object; and means to readjust each movable object to its starting position. 10. The combination with side-frames of transverse beams attached to said side-frames; means fastened to said beams to support horizontally movable objects; said objects passing intermediate the beams; driving-pins slidably attached to the beams to start movable objects; counterweighted hammers pivoted to the beams to strike said driving-pins and start said movable objects; means intermediate said driving-pins to return them to normal; means remote from the beams to operate each movable object independently; cords connecting each operating device with each of the starting de-
- 70 75 80 85 90 95 100 105 110 115 120 125 130

4
vices; means to stop each movable object attached intermediate the beams; and levers pivoted to the beams to readjust each movable part to its starting position independently of each other part.

11. The combination with side-frames of transverse beams attached to said side-frames; means fastened to said beams to support movable pendant objects; said movable objects passing intermediate the beams; devices attached to the beams to start said movable objects; operating parts remote from said beams and side frames; means to connect said operating parts with the starting devices; means within the frames to maintain each movable part in a substantially vertical position; and means to stop and release each movable part fastened to the beams.
12. The combination with side-frames of transverse beams attached to said side-frames; means fastened to said beams to

support movable pendant objects; said movable objects passing intermediate the beams; devices attached to the beams to start each movable object; operating parts remote from the beams and side-frames; means to connect said operating parts and starting devices; means within the frame to maintain each movable part in a substantially vertical position; means to prevent said movable objects from disengaging the supporting means; means to stop and release each movable part; and means to return each movable object to its starting position attached to the beams.

In testimony that I claim the foregoing as my own, I hereunto affix my signature in the presence of two subscribing witnesses.

FRED O. PERMIN.
